United States Patent Office.

SAMUEL KELLETT, OF SAN FRANCISCO, CALIFORNIA.

Design No. 4,965, dated May 30, 1871.

DESIGN FOR CENTER-PIECE.

The Schedule referred to in these Letters Patent and making part of the same.

To all whom it may concern:

Be it known that I, SAMUEL KELLETT, of San Francisco, in the county of San Francisco and State of California, have invented or produced a new Design for Center-Piece in alto-relievo; and I do hereby declare that the following is a full and exact description of the same, reference being had to the accompanying drawing and to the letters of reference marked thereon.

The drawing, consisting of only one figure, represents my new design.

This design consists of a rosette, B, with sides of shell-work, and is attached to radial arms *a*, terminating in scroll-work *b*, upon a beaded and shell-worked edge, *c d*, with intervening knobs *d'*.

Upon one of these arms, and alternating between each series of two arms, is placed a bouquet of roses and leaves, *f*, and a fruit-piece, *g*.

From these bouquets and fruit-pieces extend, at each or both sides, a cord or twisted rope, *h*, which passes around an arm of the scroll-work or arabesque *b*, with ends *i* protruding.

The edge of the scroll-work is provided with balusters *j k* projecting or extending from the arms *a*.

Having thus described my invention or production, What I claim, and desire to secure by Letters Patent, is—

The design for a center-piece, as described and shown.

In witness whereof I have hereunto set my hand and seal.

SAML. KELLETT. [L. S.]
